UNITED STATES PATENT OFFICE.

GEORGE W. WIESEHAN, OF CLEVELAND, OHIO.

COOKING-CABINET.

1,343,539.

Specification of Letters Patent. Patented June 15, 1920.

Application filed November 21, 1919. Serial No. 339,738.

To all whom it may concern:

Be it known that I, GEORGE W. WIESEHAN, a citizen of the United States, residing at Cleveland, in the county of Cuyahoga and State of Ohio, have invented certain new and useful Improvements in Cooking-Cabinets, of which the following is a specification.

This invention relates to an improvement in cooking cabinets, and is particularly adapted for use in connection with that type of cabinet shown and described in a prior patent issued in my name date of November 24, 1914, and being numbered 15 1,118,607.

The object of this invention is to provide a compartment in the upper part of this type of cabinet in which a cooking stove may be inclosed and when so inclosed, will 20 effectively conceal the same and permit of the cabinet being used as a sideboard or buffet. The cabinet is so constructed as to present a pleasing appearance when closed and one which when open will permit of the 25 various closures being utilized for shelves or so positioned as to be entirely out of the way of the user.

Further objects of the invention are to provide a means whereby the closure can 30 be easily manipulated from the exterior, and in the provision of means whereby the gas may be positively shut off when the stove is not in use, thus preventing any possibility of leaving the stove burning when 35 the same is inclosed.

With these and other objects in mind the invention consists in the construction and combination of parts shown in detail in the drawings, described and particularly pointed 40 ed out in the accompanying claims.

Referring to the drawings wherein like reference numerals designate similar parts of reference throughout the various views, Figure 1 is a front elevation of a cabinet, 45 certain parts being broken away for clearness of illustration; Fig. 2 is a transverse section indicated by the line 2—2 of Fig. 1 and Fig. 3 is a horizontal section indicated by the line 3—3 of Fig. 2.

The invention comprises a cabinet which is made with upper and lower compartments 1 and 2. The lower compartment 2 provided with shelves and racks is used merely for the storing of sundry articles, 55 such as dishes and cooking utensils, and will need no further description. The up-

per compartment 1 is so constructed as to completely inclose the cooking stove, (shown in dotted lines in the drawings) and consists of a back 3, top 4 and front 5. The 60 top 4 is preferably divided from front to back at the central portion of the cabinet and the sections so formed are hinged to the side members 6 in such a manner as to permit of the same being swung upwardly and 65 outwardly until they assume the position shown dotted in Fig. 1, and in this position they form in effect shelves and may be used for the placing of dishes when the stove is in use for cooking.

The stove is mounted upon a platform which is spaced from the partition 8 between the upper and lower cabinets sufficient to allow a board 9 to be housed therein. This board may be provided with a 75 handle 10 whereby the same may be pulled outwardly to provide a table which will be found a convenient place upon which to place the cooking dishes. The front 5 has secured to its inside face and at each end a 80 pair of bracket arms 12 which are hinged upon studs 11 carried by the sides 6. The bracket arms 12 each have integral therewith a gear segment 13, and said segment 85 meshes with a second segment 14 which is mounted upon a shaft 15 extending across the cabinet and to the rear of the stove and at each end of the compartment is provided with suitable bearings 16 fastened to the sides 6. The gear segments 13 and 14 are 90 duplicated at each end of the compartment, which it will be understood, will prevent any binding and will equalize the strain upon the shaft when the cover is raised. At one side of the compartment the shaft 95 15 projects to the exterior of the cabinet and has secured thereon a crank 17 provided with an operating handle 18 whereby the segment upon the shaft may be conveniently rotated. It will thus be seen that after the 100 covers 4 have been swung to their outward position that any downward pressure upon the crank 17 will cause the gear segments to rotate in such a manner as to swing the front 5 upwardly and over the stove until 105 the top edge 20 rests upon the top edge 21 of the back 3. The front then assumes a position as shown in dotted lines in Fig. 2 and serves as a shield to protect the walls or other surroundings from becoming spattered with grease and the like, the inside of 110 the compartment and the inside faces of

the parts 4 and 5 being covered with zinc, white enamel or the like in order to provide a clean and sanitary condition but this is not essential.

5 To prevent the closing of the compartment 6 while the gas is ignited a shut off valve 22 is provided in the supply pipe 23, said valve is provided with a bifurcated operating lever 24, the forked end of which is 10 engaged by a pin 25 carried by an extension 26 of the gear segment 14. As shown in Fig. 2 the valve is in its normal or closed position and it will be seen that upon rotating the segment in the direction of the arrow 15 the valve lever 24 will be turned in a direction to allow the gas to enter the manifold 27 of the stove.

While I have shown and described this particular construction it is evident that 20 various means may be employed to accomplish the same purpose, and I do not wish to limit myself further in the construction of the same than is required by the state of the art or that which comes within the scope 25 of the appended claims.

I claim:

1. The combination with a cabinet hav-

ing a swinging front, of a gear attached to said front, an operating crank shaft extending through a wall of the cabinet and having a gear meshing with said gear and adapted to swing the front open when the crank shaft is turned, and a gas stove in the cabinet having a fuel supply pipe provided with a valve, and an operating connection 30 between the crank shaft and the valve. 35

2. The combination with a cabinet having a vertically swinging front, brackets attached to the front and pivoted to the ends of the cabinet, a gear fixed to one of said brackets, a crank shaft extending through the end of the cabinet, a gear fixed to the shaft and meshing with said gear, a gas stove burner in the cabinet, having a supply pipe provided with a valve, and an operating 40 connection between one of said gears and the valve, to open and close the latter when the front is opened and closed. 45

In testimony whereof I do affix my signature in presence of two witnesses.

GEORGE W. WIESEHAN.
